MACHINE FOR SHARPENING ROTARY CYLINDRICAL CUTTERS

Marie C. McCormack, New Orleans, La.

Application February 7, 1940, Serial No. 317,744

8 Claims. (Cl. 51—161)

This invention relates to a sharpener for rotary or cylindrical cutters or knives such as, for example, the knives used in pencil sharpeners, cylindrical reamers, cutting tools, and the like having axially or spirally extending blades about a cylindrical body portion. Knives of this type are oftentimes arranged to operate in pairs, and it is important that both knives or cutters of each pair have the same overall diameter and uniform cutting edges.

An object of the invention is to provide a sharpening device or apparatus for cutters or knives of the type specified which will permit a rapid or relatively quick sharpening operation and which at the same time will result in a uniform cutting edge throughout the length of the blades of the cutter to be sharpened.

Another object is to provide a sharpening apparatus for cylindrically arranged knives or blades whereby the latter may be expeditiously sharpened in pairs with the blades of both pairs sharpened uniformly throughout their lengths.

Generally stated, the invention contemplates a sharpener for knives or blades of the type specified wherein a pair of coacting sharpening abrasives or hones are yieldingly urged against the blades or knives to be sharpened at diametrically opposite points and under equal and uniform pressure, means being provided whereby the hones may be reciprocated longitudinally or axially of the blades during the sharpening operation.

Further and additional objects include the provision of sharpening apparatus for blades of the type specified which is simple in construction and rapid yet accurate in its sharpening operation, is capable of accommodating knives or cutters in pairs and of varying lengths, is relatively low in cost of manufacture, and embodies relatively few parts which are easily replaceable and will give long and efficient service.

The foregoing and other objects and advantages will become apparent in view of the following description taken in conjunction with the drawings, wherein:

Fig. 1 is a view in end elevation of a sharpener for rotary or cylindrical knives constructed in accordance with the features of the present invention;

Fig. 2 is a top plan view of Fig. 1;

Fig. 3 is a view in side elevation; and

Figs. 4 and 5 are sectional views taken substantially on the lines 4—4 and 5—5, respectively, of Fig. 3.

Referring to the drawings in detail, the refer-

ence character 10 generally indicates the frame of the machine which may be in the form of a casting having a base 10^a and an upright portion 10^b, the opposite edges of the base having projecting therethrough screw bolts 11 by means of which the machine may be anchored to a suitable support.

The frame or casting 10, as shown herein is formed with a pair of bearing bosses 12 and 13, each of which has a bearing therein through which knife holding shafts 14 and 15 project. These shafts 14 and 15 are provided with blade mounting portions 14^a and 15^a which in the present instance are shown as threaded to receive the cylindrical blades or knives to be sharpened, a pair of which are indicated at B and B' in Fig. 2. The blades or knives to be sharpened in this instance are those used in a pencil sharpener and which have their interior bores threaded. The shafts 14 and 15 are provided with stop shoulders or thrust bearing portions 14^b and 15^b, which obviously may be separate nuts or bearing collars instead of being formed integrally with the shaft.

The outer ends of shafts 14 and 15 have secured thereon pulleys 16 and 17 which are driven from a pulley wheel 18 mounted on a stub shaft 19, the latter being mounted in a bearing boss 20. The pulley wheel 18 has trained thereover a belt 21 which is also trained over the pulleys 16 and 17 so that when the wheel 18 is rotated, the shafts 14 and 15 are in turn rotated simultaneously and in the same direction. Wheel 18 may be power operated but is here shown provided with a handle 22 for manual operation.

A pair of abrasive devices or hones are indicated at 23 and 24, said hones each being mounted in holders 25 and 26 of similar construction which at their undersides are formed with dovetail guides 25^a and 26^a which engage in slideways or grooves 27 and 28 formed in a carrying or supporting block 29.

Block 29 is mounted for sliding movement with respect to the shafts 14 and 15, and with this in view it has a dovetail shaped rib 30 formed on the underside thereof which engages in a like shaped groove or slideway 31 formed in the base 10^a of the casting 10. The rib 30 is extended rearwardly of the block 29 so that when the block is in fully retracted position, the rear end of the rib 30 contacts the rear upstanding wall 10^b of the 10, note Fig. 4. At the front of the block, the rib terminates flush with the adjacent end wall of the block. The underside of the block 29 is provided with ribs 29^a which project later-

ally on opposite sides of the rib 30 in line with the grooves 27 and 28 and strengthen the block in the region of said grooves. These ribs 29^a slide on the base 10^a and also steady the block 29.

It will thus be seen that the hone or abrasive holders 25 and 26 are mounted for independent sliding movement towards and from the knives or cutters B and B', while at the same time they may be moved or reciprocated as a unit axially of said knives or cutters. To ensure an equal application of sharpening pressure of the hones with respect to the knives, a spring 33 is connected to the holders 25 and 26 and at its opposite ends is anchored to screws 34 and 35 which project through said holders and are adapted to engage the hones and hold them in proper position with respect to the cutters or knives B, B' to be sharpened.

The cutters or knives B and B' may be maintained in position on the chuck portions 14^a and 15^a of the shafts 14 and 15 by means of wing nuts 36, as clearly shown in Fig. 2.

To operate the machine, the cylindrical knives or cutters to be sharpened are inserted on the chuck portions 14^a and 15^a of the shafts 14 and 15, and the wing nuts 36 then tightened down to hold the knives securely in sharpening position. Although the chuck portions 14^a and 15^a of the shafts 14 and 15 are shown threaded, it will be understood that they could be formed smooth if desired to accommodate cylindrical cutters having smooth bores or even threaded bores. When inserting the knives to be sharpened, the spring 33 may be removed, or else the hones may be retracted just sufficiently to clear the knives or cutters and then released. The drive wheel 18 is then rotated, causing the cutters to revolve rapidly in contact with the hones until the sharpening operation is completed. The ratio of the pulley wheel 18 with respect to the pulleys 16 and 17 is preferably such as to result in a relatively high speed of rotation of the shafts 14 and 15. Since the spring 33 exerts an equal tension on the hones 23 and 24 and since the latter are mounted for sliding movement in their respective supports, the sharpening pressure of both hones on the blades of the knives B and B' will be equal and will result in a uniform sharpening operation with respect to both knives or cutters.

In the event the knives or cutters to be sharpened are of a length greater than the width of the sharpening edges of the hones 23 and 24, then the hones may be reciprocated axially of the shafts 14 and 15 during the sharpening operation, the pressure still remaining uniform with respect to both knives.

Whenever it is desired to remove the hones 23 and 24, it is only necessary to retract the screws 34 and 35 and release the spring 33, whereupon the hones may be readily removed from their holders 25.

The parts of the sharpener are relatively few in number, simple in construction, yet withal a highly efficient sharpening action and uniform with respect to both cutters of each pair is assured.

It will be understood that certain changes in construction and design may be adopted without departing from the spirit or scope of the invention as defined by the appended claims.

What is claimed is:

1. In a machine for sharpening rotary or cylindrical knives or cutters, a frame, a pair of spindles mounted in substantially axial parallel relation for rotation in said frame and having

portions constituting chucks on which the knives or cutters to be sharpened may be mounted, a pair of abrasives or hones slidably mounted in spaced relation substantially perpendicularly to and on opposite sides of the axes of said chucks, a spring common to both abrasives or hones normally urging the latter uniformly against the cutters or knives to be sharpened, and means for rotating said spindles.

2. In a machine for sharpening rotary or cylindrical knives or cutters, a frame, a pair of spindles or shafts mounted in substantially axially parallel relation for rotation in said frame, said spindles having portions constituting chucks on which the knives or cutters to be sharpened may be mounted, a pair of sharpening hones, holders for said hones slidably mounted on opposite sides of and in a plane substantially perpendicular to the axes of said chucks, a spring connecting at opposite ends to said holders yielding urging the latter together with the hones towards the knives or cutters to be sharpened, means supporting said holders together with said hones bodily as a unit, said latter means being mounted for sliding movement in said frame in an axial direction with respect to said chucks, and means for rotating said spindles.

3. In a machine for sharpening rotary or cylindrical knives or cutters, a frame, a pair of spindles mounted in substantially axially parallel relation for rotation in said frame, said spindles having portions projecting outwardly and constituting chucks on which the knives or cutters to be sharpened may be mounted, a pair of sharpening hones, holders for said hones slidably mounted on opposite sides of and in a plane substantially perpendicular to the axes of said chucks, means resiliently urging said holders together with the hones towards the knives or cutters to be sharpened, means supporting said holders together with said hones as a unit, means mounting said supporting means for sliding movement in an axial direction with respect to said chucks and whereby the hones may be moved axially of the knives or cutters to be sharpened, and means for rotating said spindles.

4. In a machine for sharpening rotary or cylindrical knives or cutters, a frame, a pair of spindles mounted in substantially axially parallel relation for rotation in said frame, said spindles having portions projecting outwardly and constituting chucks on which the knives or cutters to be sharpened may be mounted, a pair of sharpening hones, holders for said hones mounted for sliding movement in a direction substantially perpendicular to the axes of said chucks, a spring connected at opposite ends, respectively, to said holders and whereby the hones are yielding urged against the knives or cutters to be sharpened uniformly and equally throughout the sharpening operation, a frame block in which said holders are slidably mounted, said frame block being also slidably mounted but in a direction axially of said chucks and whereby the hones may be reciprocated along the length of the knife or cutter to be sharpened, and means for rotating said spindles.

5. In a machine for sharpening rotary or cylindrical knives or cutters, a frame, a pair of spindles mounted in substantially axially parallel relation for rotation in said frame, said spindles having projecting portions constituting chucks on which the knives or cutters to be sharpened may be mounted, a pair of sharpening hones, holders for said hones mounted for sliding move-

ment in a plane perpendicular to the axes of said chucks and whereby the holders together with the hones may be moved toward and away from the knives or cutters to be sharpened, a spring connected at opposite ends, respectively, to said holders and whereby the hones are yieldingly urged with uniform pressure against the knives or cutters to be sharpened, a frame block being mounted in a guideway extending axially with respect to said chucks and spindles, and means for simultaneously rotating said spindles.

6. In a machine for sharpening rotary or cylindrical knives or cutters of the type having an axial bore therethrough, a frame, a pair of spindles mounted in substantially axially parallel relation for rotation in said frame, said spindles having projecting portions on which the knives or cutters to be sharpened may be mounted, a pair of sharpening hones, holders for said hones, a frame block having guideways therein extending in a plane at substantially right angles to the axes of said spindles, said holders being slidably mounted in said guideways, a spring connected at opposite ends, respectively, to said holders and yieldingly urging the latter towards the spindles, said frame block being mounted in a guideway formed in said frame, said guideway extending in a direction substantially parallel to the axes of said spindles, and whereby the hones may be

moved bodily as a unit along the full length of the knife or cutter to be sharpened, and means for simultaneously rotating said spindles.

7. In a machine for sharpening rotary or cylindrical knives or cutters, a frame, a pair of chuck members rotatably mounted in said frame and adapted to support the knives or cutters to be sharpened in substantially axial parallel relation, sharpening abrasives or hones disposed in spaced relation on opposite sides of the axes of said chuck members and mounted for movement substantially perpendicularly to the knives or cutters, spring means urging said abrasives or hones uniformly against the knives or cutters, and means for rotating said chuck members.

8. In a machine for sharpening rotary or cylindrical knives or cutters, a frame, a pair of spindles mounted in substantially axial parallel relation for rotation in said frame and adapted to support the knives or cutters to be sharpened, a pair of abrasives or hones movably mounted in spaced relation substantially perpendicularly to and on opposite sides of the axes of said spindles, spring means common to both abrasives or hones normally urging the latter uniformly against the cutters or knives to be sharpened, and means for rotating said spindles.
